UNITED STATES PATENT OFFICE

1,992,018

REFRIGERATOR EVAPORATOR

Christian Steenstrup, Schenectady, N. Y., assignor to General Electric Company, a corporation of New York

Application February 24, 1933, Serial No. 658,322

7 Claims. (Cl. 62—95)

My invention relates to cooling units for refrigerating systems, and more particularly to such cooling units having a removable section which may be detached or secured to the unit without any interference with the closed circuit of the refrigerating system.

The refrigerating machines heretofore employed in household refrigerators commonly have compressor and condenser units of such capacity that they will operate satisfactorily in any one of two or more of the different standard size cabinets, the only change necessary being in the capacity of the evaporator used. It has been the practice to construct compressor and condenser units of standard sizes, each having connected thereto cooling units of a capacity selected according to the size of cabinet to be used with each compressor and condenser unit. These cooling units cannot be removed from the compressor and condenser unit without opening the closed refrigerating system, which is undesirable because air and moisture may enter the system.

When this complete refrigerating machine is installed in the field it may be desirable to place the machine in a cabinet of a size different from that for which the machine was made. This requires disconnecting and removing the cooling unit from the closed refrigerating system and connecting thereto another cooling unit of the desired capacity, which cannot be conveniently accomplished in the place where the machines are installed. This has, therefore, made it difficult to replace or repair the evaporators, if necessary, on account of leaks or damage to the enamel or other finish which is usually employed.

An object of my invention is to provide a cooling unit construction in which the capacity can be conveniently changed as desired without opening the closed refrigerating system.

Another object of my invention is to provide a cooling unit for refrigerating machines having separate sections, one of which may be attached or detached without disturbing the sealed connections between the evaporator and the refrigerating system with which it is used.

Another object of my invention is to provide a cooling unit for refrigerating systems having the main body thereof removable without disrupting the connections between the cooling unit and the remainder of the refrigerating system.

Further objects and advantages of my invention will become apparent as the following description proceeds and the features of novelty which characterize my invention will be pointed out with

particularity in the claims annexed to and forming a part of this specification.

For a better understanding of my invention reference may be had to the accompanying drawing in which Fig. 1 is a perspective view of a two-section cooling unit embodying my invention; Fig. 2 is a fragmentary longitudinal sectional view of the cooling unit shown in Fig. 1; Fig. 3 is a transverse sectional view of the lower section of the evaporator shown in Fig. 1 taken on the line 3—3 of Fig. 2; Fig. 4 is a front elevation of a household refrigerator equipped with a cooling unit constructed in accordance with my invention; and Fig. 5 is a perspective view, partly in section, of a modified form of cooling unit embodying my invention.

Referring to the drawing, in Fig. 1 I have shown a cooling unit having a primary evaporator of the flooded type comprising a header 10 provided with legs 10a for securing it to a refrigerator cabinet top, and a depending wall 11 having circulatory passages for refrigerant leaving and returning to the header 10. As shown in Fig. 2, the wall 11 comprises an inner shell 12 and an outer shell 13 provided with corrugations 14, which cooperate with the inner shell to form the refrigerant circulating passages. The header 10 is provided with an inlet 15 for admitting liquid refrigerant to the evaporator and the level of liquid refrigerant in the header is maintained above the upper end of the passages in the wall 11. The gaseous refrigerant is withdrawn from the evaporator through an outlet 16. This evaporator is of the construction described and claimed in my copending application, Serial No. 389,050, filed August 28, 1929, and assigned to the same assignee as this invention.

In accordance with my invention, I provide a second section, or secondary evaporator 17, removably secured to the section 11 by thumb screws 18, one of which is arranged on each side of the evaporator, and which are threaded on rods 19 pivoted to the secondary evaporator 17 and engaging slotted lugs 20 secured to the wall 11 of the primary evaporator. As can be seen in Figs. 2 and 3, the secondary evaporator 17 is formed of an inner shell 21 and an outer shell 22 provided with corrugations 23 in contact with the inner shell and forming refrigerant circulating passages. This secondary evaporator is also provided with transverse openings or manifolds, the upper manifold being formed by a flute 24 in the inner shell 21 and the lower manifold being formed by depressions 25 in corrugations in the outer shell 22. The secondary evap-

orator 17 is hermetically sealed and is partially filled with liquid refrigerant as indicated in Fig. 3, the remaining portion being filled with gaseous refrigerant. As can be seen in Fig. 2 corrugations 14 and 23 are made to conform and fit together, which insures sufficient direct contact of the walls to provide good heat conduction between the evaporators when thumbscrews 18 are tightened.

10 In Fig. 4 I have shown a household refrigerator comprising a condenser and compressor unit 26 mounted on a cabinet 27 within which is arranged an evaporator 28 constructed as shown in Fig. 1, and within which evaporator are arranged freezing trays 29. In the operation of this system, refrigerant is compressed and condensed to a liquid in the compressor and condenser unit 26 and flows through a flow control device 30 from whence it flows to the header 10 in regulated quantities. Heat is absorbed by the refrigerant in the evaporator section 11 and a portion of the refrigerant is vaporized thereby, and the vaporized refrigerant collects in the header 10 from whence it is drawn back into the compressor and condenser unit 26 through the suction conduit to the compressor. Since the upper portion of secondary evaporator 17 is in direct heat exchange relation with the wall 11, it is cooled thereby, and the gaseous refrigerant in this upper portion is condensed as the heat is extracted from it, and the condensate flows back to the bottom of the evaporator to the main body of liquid refrigerant therein. Heat absorbed by the liquid refrigerant in the secondary evaporator, which is extracted from the air in the refrigerator cabinet and the freezing trays vaporizes the liquid and the vapor rises and gives up its heat at the top of the section in the manner just described. This cycle is continuous.

35 40 No refrigerant is added to or withdrawn from the evaporator 17 during its operation and it is completely sealed from the rest of the system. Should the capacity of the cooling unit shown in Fig. 4 be too great for the cabinet 27, or should it be desired to use the refrigerating machine in a smaller cabinet, then the secondary evaporator 17 may be removed from the cabinet by loosening the thumbscrews 18. It is thus apparent that the evaporator, as shown in Figs. 1 and 4 is so constructed as to be available for use in either of two or more sizes of refrigerator cabinet. All the refrigerator units for either size of cabinet may be shipped from the factory with identical standard size evaporators connected in the circuit. When a refrigerator is installed, one of the standard units can be placed in the cabinet and if the cabinet is of the larger size one or more of the secondary evaporators can be attached to the primary evaporator supplied with the unit.

55 60 In Fig. 5 I have illustrated a modified form of my invention comprising a cooling unit the greater portion of which is removable without requiring the disconnection of the refrigerant circuit. I have also shown this modification as constructed of cast metal, although this is not essential to the invention, as sheet metal or other types of construction may be used. In this construction I provide an evaporator of the flooded type comprising a header 31 and a depending refrigerant circulating section 32 communicating with the header through tubes 33. The header 31 is provided with a connection 34 for admitting liquid refrigerant thereto and a connection 35 for withdrawing gaseous refrigerant therefrom. The liquid refrigerant in the

header 31 is maintained approximately at the level indicated at 36. The depending section 32 is in the form of a flat plate having a plurality of refrigerant passages formed therein. In accordance with my invention I provide a hermetically sealed removable section or secondary evaporator 37 partially filled with liquid refrigerant and having a flat top arranged to be secured in contact with the section 32 by screws 38. Within the cast walls of the evaporator 37 are formed refrigerant circulating passages 39 connected by transverse openings 40. These walls form a freezing compartment arranged to accommodate trays for freezing water, puddings, and the like. The outer surfaces of the secondary evaporator are large enough to cool the air circulated in the refrigerator cabinet in which the cooling unit is used. The operation of this modification is the same as that described in connection with the previous modification. The advantage of this modification lies in the arrangement whereby the main body of the evaporator having a compartment for trays may be removed without opening the refrigerant circuit if this becomes necessary on account of leaks or damage of the porcelain enamel or other finish employed. The main body of the evaporator is more likely to be damaged than the other portions thereof, because the ice trays freeze to the bottom of their compartments and are usually forcibly loosened.

It is evident from the foregoing that I have provided a refrigerator cooling unit of such a construction that its capacity may be changed by removal of a portion of the cooling unit without interfering in any way with the sealed refrigerant circuit, and that I have also provided a cooling unit, the main portion of which may be removed without interfering with the refrigerant circuit.

Although I have shown a particular embodiment of my invention in connection with a compression refrigerating machine and a flooded evaporator, I do not desire my invention to be limited thereto, and intended in the appended claims to cover all modifications within the spirit and scope of my invention.

What I claim as new and desire to secure by Letters Patent of the United States, is:

1. A cooling unit for a refrigerator cabinet including a primary evaporator and a hermetically sealed secondary evaporator partially filled with liquid refrigerant and removably secured thereto, said secondary evaporator having a compartment for freezing trays and having a portion above the level of liquid refrigerant in said secondary evaporator in heat exchange relation with said primary evaporator, said primary and secondary evaporators having surfaces for cooling air in the refrigerator cabinet.

2. A cooling unit for a refrigerator cabinet including a primary evaporator having a compartment for freezing trays and a hermetically sealed secondary evaporator partially filled with liquid refrigerant, said secondary evaporator having a compartment for freezing trays and having a portion above the level of liquid refrigerant in said secondary evaporator in heat exchange relation with said primary evaporator, said primary and secondary evaporators having surfaces for cooling air in the refrigerator cabinet, said secondary evaporator being removable from said primary evaporator to reduce the heat absorbing capacity of said cooling unit.

3. A cooling unit for a refrigerator cabinet

including a primary evaporator having a relatively thin flat refrigerant containing member, a header secured to said member and a hermetically sealed secondary evaporator partially filled with liquid refrigerant and having a flat surface above the level of liquid refrigerant therein in heat exchange relation with said refrigerant containing member, said secondary evaporator being removable from said primary evaporator, said primary and secondary evaporators having surfaces for cooling air in the refrigerator cabinet.

4. A cooling unit for a refrigerator cabinet including a primary evaporator having a corrugated surface and a hermetically sealed secondary evaporator partially filled with liquid refrigerant, said secondary evaporator having a corrugated portion above the level of liquid refrigerant therein in heat exchange relation with the corrugations in said primary evaporator, a portion of the corrugations on said secondary evaporator conforming to a portion of the corrugations on said primary evaporator, said primary and said secondary evaporators having surfaces for cooling air in the refrigerator cabinet.

5. A cooling unit for a refrigerator cabinet including a primary evaporator provided with a header and having a relatively thin flat refrigerant containing member, and a hermetically sealed secondary evaporator partially filled with

liquid refrigerant and removably secured in heat exchanging relation to said refrigerant containing member, said secondary evaporator having a compartment for freezing trays, said primary and said secondary evaporators having surfaces for cooling air in the refrigerator cabinet.

6. A cooling unit for a refrigerator cabinet including a primary evaporator provided with a header and a corrugated refrigerant containing member, means for supporting said primary evaporator within the refrigerator cabinet, and a hermetically sealed secondary evaporator removably secured to said primary evaporator, said secondary evaporator having a corrugated surface and being partially filled with liquid refrigerant, the corrugations of said primary and said secondary evaporators conforming to provide good heat exchange between them, said primary and said secondary evaporators having surfaces for cooling air in the refrigerator cabinet.

7. A refrigerator cabinet, a cooling unit arranged in said cabinet, said cooling unit including a primary evaporator and a hermetically sealed secondary evaporator partially filled with liquid refrigerant and removably secured to said primary evaporator in heat exchange relation therewith, said secondary evaporator having a compartment for receiving freezing trays.

CHRISTIAN STEENSTRUP.
